(57) **CLAIM**

The ornamental design for a firearm magazine protective cover, as shown and described.

DESCRIPTION

FIG. 1 is a perspective view of the firearm magazine protective cover, showing the new design;

FIG. 2 is a front elevational view of the firearm magazine protective cover thereof;

FIG. 3 is a rear elevational view of the firearm magazine protective cover thereof;

FIG. 4 is a left side elevational view of the firearm magazine protective cover thereof;

FIG. 5 is a right side elevational view of the firearm magazine protective cover thereof;

FIG. 6 is a top plan view of the firearm magazine protective cover thereof; and,

FIG. 7 is a bottom plan view of the firearm magazine protective cover thereof.

The evenly broken lines depict the unclaimed portions of the firearm magazine protective cover; the dash-dot lines disclose unclaimed boundaries of the claim; the broken lines form no part of the claimed design.

1 Claim, 3 Drawing Sheets
